ESCUtCHEON MOUNTING CLIP

Carlton F. Stute, Riverdale, Ill., assignor to Admiral Corporation, Chicago, Ill., a corporation of Delaware
Filed Dec. 10, 1965, Ser. No. 524,630
4 Claims. (Cl. 52—716)

ABSTRACT OF THE DISCLOSURE

A clip for mounting an escutcheon to a cabinet wherein the cabinet is provided with a mounting strip and the clip may be secured at any position along the mounting strip by seating one clip leg thereon and tightening a threaded fastener into the escutcheon which draws the escutcheon towards the cabinet and automatically seats the remaining clip leg on the mounting strip.

This invention generally relates to cabinet construction and assembly. In particular, this invention is concerned with a mounting clip and associated clip driving tool for rapidly, simply, economically, and rigidly securing a decorative escutcheon to the walls forming the front of a television receiver cabinet.

It is conventional in the television manufacturing industry to purchase preassembled cabinets or enclosures for housing the television receivers and picture tubes which are ultimately sold to the consumer. A decorative escutcheon surrounds the viewing portion of the picture tube and fills the space between it and the walls forming the front of the television cabinet. This escutcheon is usually purchased as a separate item from a different supplier than that of the cabinets. During final assembly of the television set, the decorative escutcheon is mated and secured to the preassembled cabinet.

A typical method of securing an escutcheon is to have the cabinetmaker provide a wooden shoulder around the interior cabinet walls, adjacent the cabinet front. The cabinetmaker also provides a series of holes through the shoulder at specific locations, lying in a front to back direction. The escutcheon is designed with bosses on its back surface, facing the shoulder, and are arranged for alignment with the holes previously provided by the cabinetmaker. On the assembly line, a fastener, such as of the self-threading type, is inserted through the hole in the shoulder and into the boss. Driving the fastener into the boss then draws the escutcheon towards the cabinet, thereby completing this phase of the assembly.

This method of securing an escutcheon to a television cabinet presented many difficulties and inconveniences. First, the cabinetmaker had to accurately drill the holes through the shoulder. Secondly, the escutcheon manufacturer had to locate the bosses in their exact locations to coincide with the shoulder holes. Misalignment of either the bosses or holes would result in an inadequately secured escutcheon, and would necessitate removal of the cabinet from the assembly line, re-drilling the shoulder, and re-setting the escutcheon. Further, unless the escutcheon and cabinet were specifically designed for each other, as is rarely the case when numerous styles and models of cabinets are available, one escutcheon could not be directly substituted for another. A series production delay could arise from this lack of interchangeability, for example, if cabinets of a particular design are available, and their exact mating escutcheons unavailable.

The disclosed invention obviates many problems present in prior methods of securing an escutcheon to a television receiver cabinet, by eliminating the holes previously required in the shoulder and substituting mounting clips of unique and novel design. In place of a drilled shoulder

2

the cabinetmaker now provides an extremely simple mounting strip on the interior of the cabinet adjacent its front. The design of the escutcheon continues to include bosses on its back surface, but their locations are relatively unimportant so long as they are of sufficient number and adequately spaced.

During assembly of the television cabinet and receiver, an escutcheon is set in place on the walls forming the cabinet front. A mounting clip is then positioned on the mounting strip adjacent each boss, and a fastener inserted therethrough. Driving the fastener into the boss seats the clip on the mounting strip and also draws the escutcheon towards its cabinet. Thus, prior alignment of the escutcheon with the cabinet is unnecessary.

Accordingly, it is the primary object of this invention to provide a means for securing an escutcheon to a television receiver cabinet without prealigning the cabinet with said escutcheon.

Another object of this invention is to provide a mounting clip for use in securing an escutcheon to a television receiver cabinet or the like.

A further object of this invention is to provide a universal assembly clip for securing any escutcheon to any television receiver cabinet of similar size without drilling holes through said cabinet.

An additional object of this invention is to provide a simplified, single-step operation for attaching a mounting clip, and securing an escutcheon, to a television receiver cabinet.

A feature of this invention resides in the use of a uniform mounting strip upon which a mounting clip may be easily attached at any location in alignment with an escutcheon boss.

The primary advantage of this invention rests in its extremely versatile application to various television receiver cabinets and escutcheons, regardless of style or size, and its novel and simple method of construction and assembly, respectively. Other objects and advantages of this invention will become apparent upon an examination of the following description taken in conjunction with the accompanying drawings wherein:

FIG. 1 is a cutaway, partially exploded perspective view of a television receiver cabinet, mounting clip, and escutcheon, incorporating an embodiment of the invention. This view is generally looking down from beyond a top rear corner of the television cabinet.

FIG. 2 is an enlarged perspective view of a mounting clip shown in FIG. 1.

FIG. 3 is an enlarged plan view, through line 3—3 of FIG. 1, of the more important elements of the television cabinet, escutcheon, clip, and mounting tool, but with the clip shown in two positions.

Turning to consideration of the drawings and in particular to FIG. 1, there is shown an ordinary television receiver cabinet 10 that includes a cabinet top wall 12, bottom wall 14, and two side walls 16 and 18. Normally the cabinet walls would be constructed of wood or a product thereof although it would be feasible to use the invention with walls constructed of metal.

A mounting strip 20, preferably of wood, is secured by a fastening device 21 to the side walls 16 and 18 inwardly of the enclosure, but adjacent the front thereof. The mounting strip includes a front side 22, and a back side 24, their respective directions each orientated with those of the television cabinet. Back side 24 is provided with a longitudinal notch or a kerf 26 at a back corner adjacent the wall to which it is secured. It is of course obvious that mounting strips may be provided along the interior top, and bottom walls if so desired, either in addition, or instead of those on the sides.

As best seen in FIG. 2, a mounting clip 30, fabricated

of magnetic permeable material, is of generally U configuration and includes a rear leg 32, a connecting portion 37 perpendicular to the rear leg, and a front leg 40. The rear leg is substantially flat and terminates with an inwardly formed lip 34 having teeth 36 at its ends. Front leg 40 forms an acute angle with connecting portion 37, and is provided with an outwardly turned perpendicular edge 42 and an extending flange 44. Aligned apertures 46 and 38 are punched through the front and rear legs, respectively, for receiving a fastener 47, having a head 48. The aperture size through the front leg is substantially larger than the diameter of the fastener to allow freedom of movement during mounting.

A decorative escutcheon or frame to be secured to the television receiver cabinet is proportioned to fit either over or within the cabinet front and is of sufficient width to fill a normal gap between the picture tube and the cabinet walls. An escutcheon of the former type is depicted in FIGS. 1 and 2 and generally referred to by reference numeral 50. Escutcheon 50 has a framework 52 encompassing its periphery and includes a backwardly projecting rail 54 terminating in a flat nose 56. A plurality of bosses 58 molded integral with the escutcheon rear, are located inwardly of the rail and face the mounting strip. These bosses are drilled to receive fasteners 47 during assembly of the television cabinet.

A driving tool 60 is used to facilitate handling and fastening the mounting clip. This tool has a shaft 62 which may be driven by an electric motor 63, a pneumatic device, or manually, and terminates in a magnetic, socket-like driving head 64 adapted to receive the fastener heads. A magnetic collar 66, surrounding the driving head and having an oblique face 67, is pivotally secured to shaft 62 thereby allowing it to remain stationary during rotation of said shaft. The collar is also adapted to slide longitudinal along the shaft to either enclose, or partially expose, the driving head in a telescope-like manner. A tab 68 is located at one edge of the collar to assist in positioning the clip, while a coil spring 70 connects the collar to a bearing 72. The coil spring allows the socket head to protrude beyond the oblique face when a longitudinal force is exerted on shaft 62.

After the mounting strips have been secured to the walls of the television cabinet, the escutcheon is placed in its assembled position, that is, with nose 56 of rail 54 abutting front side 22 of the mounting strip, as shown in FIG. 3. The magnetic mounting clip, having a fastener extending through its apertures, is then placed on the driving tool with back leg 32 resting against the oblique face and the fastener head partially engaged in the driving head. Tab 68 supports connecting portion 37 of the clip, which may now be handled and moved merely by grasping the driving tool.

To anchor the mounting clip and escutcheon to the cabinet, an operator slides the clip forwardly, along the cabinet wall until teeth 36 and lip 34 engage the kerf 26, and flange 44 rubs along an inward edge of the mounting strip. This position of the clip is shown in FIG. 3 in dashed lines. As the operator slides the clip towards the mounting strip he will of course aim the end of the fastener towards a hole in one of the escutcheon bosses. By driving the fastener into its boss, the whole clip is pulled towards the escutcheon. Teeth 36 dig into the material forming the notch, thereby preventing movement of the clip along the mounting strip, and the legs are spread sufficiently to allow flange 44 to drop along front side 22. Turned out edge 42 limits the distance the flange can drop along this side.

After the mounting clip has been initially anchored to the mounting strip, and is retained in place only by the resilient construction of the clip, further tightening of the fastener draws the escutcheon boss adjacent the front leg.

Driving the fastener deeper into the boss squeezes the clip legs together and securely anchors it to the mounting strip, thereby firmly holding the escutcheon in place.

What has been described is an inexpensive, reliable, simple, and novel mounting strip and clip for securing any properly sized escutcheon to a television receiver cabinet of similar size.

It is obvious that upon study by those skilled in the art, the disclosed invention may be altered or modified both in physical appearance and construction without departing from its inventive concept. Therefore, the scope of protection to be given this invention should not be limited by the embodiment described above, but should be determined by the essential descriptions thereof which appear in the appended claims.

The embodiments of the invention in which an exclusive property or privilege is claimed are defined as follows:

1. In combination: an enclosure defining an opening; a mounting strip, having two sides, bordering said opening; a frame adjacent said mounting strip for attachment thereto in closing relationship to said opening; a resilient mounting clip having a pair of opposed legs each defining an aperture; a fastener, co-operable with said clip through said apertures, for mounting said clip to said frame, one 10 of said apertures being sufficiently large to allow pivotal movement of said clip with respect to said fastener; said clip having one leg engaging one side of said mounting strip and pivoting thereabout as said fastener urges said frame and said enclosure towards each other, whereby 15 under further urging of said fastener the remaining leg snaps into resilient engagement with the other side of said mounting strip and said frame is drawn into mounted relationship with said enclosure.

2. In combination: an enclosure defining an opening; a mounting strip at least partially bordering said opening, interior of said enclosure; a frame adjacent said opening having a boss thereon extending into said cabinet juxtaposition said mounting strip; a normally concealed substantially U-shaped resilient clip having legs straddling 20 and gripping said mounting strip; each of said legs defining apertures; a normally concealed threaded fastener extending through said apertures, whereby when said fastener is threaded into said boss, said frame is drawn into mounted relationship with said enclosure and the legs of 25 said clip are tightly compressed on said mounting strip.

3. The combination as set forth in claim 2 wherein when a first of said clip legs is seated on said mounting strip and said frame is drawn into mounted relationship with said enclosure by said fastener, the remaining leg is automatically urged into straddling relationship with said mounting strip.

4. The combination as set forth in claim 3 wherein said first clip leg includes a lip, and wherein said mounting strip includes a kerf receiving said lip, said lip and kerf 55 cooperating to prevent movement of said clip away from said mounting strip in a direction parallel to said clip legs.
